CLAIM

The ornamental design for an endpoint for a videoconference, as shown and described.

DESCRIPTION

FIG. 1 is a front perspective view of the endpoint for a videoconference embodying our new design.

FIG. 2 is a perspective view from above of the endpoint for a videoconference.

FIG. 3 is a back view of the endpoint for a videoconference.

FIG. 4 is a top view of the endpoint for a videoconference; and,

FIG. 5 is a side view of the endpoint for a videoconference, the opposite side being a mirror image.
